UNITED STATES PATENT OFFICE.

JOSEPH M. MOORE, OF CHATHAM, ILLINOIS.

TELEPHONE-TRANSMITTER.

SPECIFICATION forming part of Letters Patent No. 651,198, dated June 5, 1900.

Application filed September 23, 1899. Serial No. 731,436. (No model.)

To all whom it may concern:

Be it known that I, JOSEPH M. MOORE, of Chatham, in the county of Sangamon and State of Illinois, have invented a new and 5 Improved Telephone-Transmitter, of which the following is a full, clear, and exact description.

This invention relates to improvements in transmitters for electric telephones; and the 10 object is to provide a transmitter of suitable construction and very sensitive and uniform in its operation.

I will describe a telephone-transmitter embodying my invention and then point out the 15 novel features in the appended claims.

Reference is to be had to the accompanying drawings, forming a part of this specification, in which similar characters of reference indicate corresponding parts in all the figures.

20 Figure 1 is an elevation of a transmitter embodying my invention. Fig. 2 is a section on the line 2 2 of Fig. 1. Fig. 3 is a sectional detail showing the carbon tubes and balls connecting opposite electrodes, and Figs. 4 and 5 are respectively a sectional side elevation and a front elevation of a modification.

Referring to the drawings, 1 designates the front board of the transmitter, and secured to the rear side thereof is the diaphragm 2.

30 The diaphragm is secured in place by means of a ring 3 extending around its edge, through which screws 4 pass into the front board, and arranged on the back of the diaphragm is a textile material 5—such, for instance, as felt—35 designed to damp excessive vibration of the diaphragm. This textile material is held in place by means of a plate 6 at the center of the diaphragm and through which a fastening-screw 7 passes, the said screw also passing through the diaphragm.

40 Mounted rearward of the diaphragm are two pairs of electrodes 8 and 9 and 10 and 11. Fastening-bolts 12 pass through the head portions of these electrodes and also through a central 45 strip 13 of insulating material, and the electrodes are suspended from a bolt 13^a, extended rearward from the front board 1 by means of spring-plates 14 and 15, connecting, respectively, with the binding-posts 16 and 17, to which the 50 line-wires are designed to be connected. The electrodes 8 and 9 are connected by a tubu-

lar bridge 18 of carbon, and placed within said tubular bridge is a series of carbon balls 19, designed to increase the number of loose contacts. The electrodes 10 and 11 are also 55 connected together by a tubular bridge 20 of carbon, within which carbon balls 21 are placed. The electrodes extend into the ends of the tubular bridges, and, as plainly indicated in Fig. 3, the openings within the 60 bridges are tapered from the center outward—that is, the outer ends are larger in diameter than the inner ends or central portion. This is to cause the balls to roll outward to engage against the beveled ends of the electrodes for 65 yielding pressure. The pressure of the tubes 18 and 20 against the electrodes and also against the diaphragm is regulated by turning the weight 22 on the screw 23, extended from the lower end of a pressure-pendant 24, 70 which is adjustably attached to a screw-rod 25, extended rearward in the front plate 1. It is to be understood that the normal set of the inner tube 20 is slightly away from the diaphragm or rather slightly away from the 75 end of the screw 7.

In Figs. 4 and 5 I have shown but two electrodes 26 and 27. These are mounted on springs 14, like the example first described, and in this instance the carbons are bridged by a 80 bunch of platinum wire 28, attached to the pendant 24.

A transmitter made in accordance with my invention may be used with two or more cells of a battery and it is found very sensitive 85 and powerful.

Having thus fully described my invention, I claim as new and desire to secure by Letters Patent—

1. In a telephone-transmitter, a diaphragm, 90 electrodes rearward of the diaphragm, a spring-arm supporting the electrodes, a bridge between the electrodes, and a pressure-regulator rearward of the electrodes, substantially as specified. 95

2. A telephone-transmitter, comprising a diaphragm, electrodes rearward of said diaphragm, spring-arms suspending said electrodes, a tubular bridge connecting the electrodes, and carbon balls in said bridge, substantially as specified. 100

3. A telephone-transmitter, comprising a

2
diaphragm, two pairs of electrodes rearward of the diaphragm, carbon tubes bridging opposite electrodes, the openings in said tubes being flared from the center outward, carbon 5 balls in said tubes, spring-plates suspending the electrodes, and an adjustable pendant for regulating the pressure on the electrodes, substantially as specified.

4. A telephone-transmitter, comprising a 10 front plate, a diaphragm secured to said front plate, a disk of felt or the like, on the rear side of the diaphragm, a bolt passing through the center of said disk and also through the dia-

phragm, and electrodes suspended rearward of the diaphragm, substantially as specified. 15

5. A telephone-transmitter comprising a diaphragm, electrodes rearward of the dia- 20 phragm, means for yieldingly supporting the electrodes, a tubular bridge connecting the electrodes, and movable devices in the bridge, substantially as specified.

JOSEPH M. MOORE.
